Atkins.

UNITED STATES PATENT OFFICE.

LEWIS E. CURTIS, OF MILWAUKEE, WISCONSIN, ASSIGNOR TO THE YOUNGSTOWN PRESSED STEEL COMPANY, A CORPORATION OF OHIO.

EXPANDED-METAL LATH.

Application filed June 30, 1924. Serial No. 723,183.

The present invention relates to improvements in expanding metal, and more particularly in methods for the manufacture of expanded metal rib lath. It will be fully understood from the following description, illustrated by the drawings, in which:

Figure 1 is a plan view of a portion of a blank;

Fig. 2 is an end view of the blank;

Fig. 3 is a plan view of the portion of the blank shown in Fig. 1 after the initial step of the process, the formation of certain of the intermediate ribs;

Fig. 4 is an end elevation of the blank as shown in Fig. 3, portions of the rib forming rolls or dies being diagrammatically shown;

Fig. 5, is a plan view of the portion of the blank shown in Figs. 1 and 3, after the cutting or slitting operation;

Fig. 6 is a plan view of the portion of the blank shown in Figs. 1, 3 and 5, after the formation of the remaining intermediate and the marginal ribs;

Fig. 7 is an end view of the blank at the stage shown in plan in Fig. 6;

Fig. 8 is a plan view of the portion of the blank shown in Figs. 1, 3, 5 and 6, after the expanding operation;

Fig. 9 is an end view of the expanded lath shown in plan in Fig. 7; and

Fig. 10 is an enlarged detail view showing the mesh formed by expansion.

In carrying out the present invention, a flat blank of the desired width and length and of the desired gage of metal is initially formed with at least one intermediate rib, and preferably a plurality of ribs or grooves 10 as shown in Fig. 3. These ribs may suitably be formed by passing the flat blank of Fig. 1 through tongued and grooved rolls 11 and 12, or through other suitable dies. The ribs 10 are suitably formed at intermediate points in the width of the blank, and as illustrated, are preferably symmetrically disposed with respect to the center line of the sheet. After formation of the ribs 10, the sheet is subjected to a slitting or cutting operation for

the formation of the slits 13, which, in the metal illustrated, are in herringbone relation. In the slitting operation the blank may be moved intermittently or continuously through the cutting dies, as desired, the ribs 10 being used to guide the blank through the cutters. The slits 13 are suitably formed in the sheet in such manner as to provide intermediate stay portions 14 and selvage portions 15.

The slitted sheet is next passed through suitable dies, for example, rolls of the mating tongued and grooved type as shown at 11 and 12 in Fig. 4, for the formation of ribs at the intermediate stay portions 14 and at the selvage portions 15. As shown in Fig. 7, alternating ribs are preferably oppositely grooved, certain of the intermediate ribs, for example, ribs 10 and 16 being higher than the selvage or marginal ribs 15^a formed by the selvage portions 15. It is preferred that the marginal ribs 15^a be approximately one-half the height of the intermediate ribs referred to.

After formation of the intermediate and marginal ribs, as shown in Figs. 6 and 7, the metal is expanded suitably by lateral expansion, assuming the form shown in Fig. 6, the mesh 17 (shown in enlarged scale in Fig. 9) being formed by the opening of the slits 13. The expanded lath is rigid and plaster-saving, particularly where adjacent sheets are overlapped, the small marginal ribs avoiding excessive thickness of plaster and also avoiding protrusion of the lath through the plaster.

I claim:

An expanded metal lath comprising spaced longitudinal sections of expanded metal and ribbed stays between said expanded metal sections and at the margins of the sheets, the ribs at the margins of the sheets being lower than certain of the central ribs so that when the edges of two contiguous sheets overlap, the combined height of the overlapped sheets is less than the height of said central ribs.

LEWIS E. CURTIS.

CERTIFICATE OF CORRECTION.

Patent No. 1,655,091.

Granted January 3, 1928, to

LEWIS E. CURTIS.

It is hereby certified that the above numbered patent was erroneously issued to "The Youngstown Pressed Steel Company, a Corporation of Ohio", whereas said Letters Patent should have been issued to "A. C. Paul, of Minneapolis, Minnesota and George A. Chritton, of River Forest, Illinois, Trustees, as assignees by mesne assignments of the entire interest in said invention", as shown by the records of assignments in this office; and that the said Letters Patent should be read with this correction therein that the same may conform to the record of the case in the Patent Office.

Signed and sealed this 13th day of March, A. D. 1928.

Seal.

M. J. Moore,
Acting Commissioner of Patents.
